UNITED STATES PATENT OFFICE.

WILLIAM WALLACE CALDWELL, OF FALL RIVER, MASSACHUSETTS, ASSIGNOR TO THE AMERICAN THREAD COMPANY, OF NEW YORK, N. Y., A CORPORATION OF NEW JERSEY.

SPINNING-MACHINE.

1,122,231.

Specification of Letters Patent. Patented Dec. 22, 1914.

Application filed July 1, 1914. Serial No. 848,407.

To all whom it may concern:

Be it known that I, WILLIAM WALLACE CALDWELL, a citizen of the United States, residing at Fall River, Bristol county, State 5 of Massachusetts, have invented certain new and useful Improvements in Spinning-Machines, of which the following is a full, clear, and exact description.

This invention relates to spinning machinery and is particularly applicable to twisting frames and the like employing wet twisting.

The present invention aims to improve the wetting action and is described in detail in 15 the following specification taken in connection with the accompanying drawing illustrating my improvement and forming part of the specification.

In these drawings Figure 1 is a vertical 20 sectional view through a frame embodying my improved construction, parts being shown in elevation and diagrammatically. Fig. 2 is a fragmentary perspective view of the trough or receiver for the excess liquid 25 extracted from the thread. Fig. 3 is a detail perspective view of a combined checking and guiding block coöperating with the trough to conduct the excess liquid thereto.

In the preferable form, I place the feed 30 rolls on the dry side of the wetting trough and provide a receptacle in addition to the wetting trough for the excess water, together with means for extracting the excess water and conducting it to this receptacle, and also 35 means for guiding the thread as it comes from the wetting trough.

In the drawings 1 designates supporting 40 means for a plurality of spools 2, from which the thread is drawn through suitably supported eyes 3, and is passed under a lower feed roller 4 and up and around an upper feed roller 5, both of these feed rollers being supported by and journaled in a suitable support 6. Suitably supported on the 45 frame forwardly of the feed rolls 4-5, is a wetting trough 7, preferably having a removable lining. Mounted within the trough at the edge adjacent the feed rolls and extending longitudinally of the trough, is a 50 guide 8 preferably in the form of a rod of glass or porcelain. This guide rod is within and below the trough with its under face below the normal water level therein. A supporting bracket positioned outside of the 55 trough 7 is provided, a convenient method

being to extend the far edge of the trough 7 to form a support and to mount on this support a bracket 9. Other supporting means could be employed, but the one described forms the most convenient one, the main object being to provide a support for an excess liquid receptacle, positioned beyond or outside of the trough 7. Secured to the upright flange of the bracket 9 by suitable means is an excess liquid receptacle in the 60 form preferably of a metal trough 10 extending substantially the length of the wetting trough 7 and of the guide 8, this receptacle preferably having its ends closed by shallow walls 10^a and being provided 65 with a liquid discharge means such as the tube 11. The sides of the trough are longitudinally corrugated to form guiding tongues 12. The trough being of metal, affords a slight spring action at its upper 70 ends where these tongues are located, so that the thread guiding blocks 13 may be held between the sides of the trough. In order to effectively do this, these blocks adjacent 75 their bases are provided with grooves 14 therein complementary to the tongues 12, the thickness of the blocks being such that they 80 may be forced longitudinally of the trough, the tongues 12 thereof having a friction 85 tight engagement in the grooves 14 of the blocks. These blocks are preferably formed 90 of porcelain, although other materials may be used, and have their inner faces rounded in the direction of the guide 8, and provided with thread guiding grooves 15 therein. 95 Each of the blocks is provided with a vertical bore 16 therethrough, which, at the upper end of the block is counter-sunk, its counter-sunk edge communicating with the 100 groove 15. The lower extremity of the bores 16 are positioned within the trough 10 as will be evident. I prefer to employ a plurality of these blocks 13, the number of these 105 blocks corresponding to the number of threads, but it will be evident that a single block could be provided having the requisite number of guiding grooves and bores 16. The threads passing under the roller 8 will be drawn over and through the grooves 15 of the blocks, and thence downwardly and 110 preferably through an eye 17 to a spinning ring or a twister 18 conventionally shown.

A better twisting action may be had if the threads are free as possible from any substance which would tend to make them stiff

and gummy. These threads contain more or less soluble vegetable matter as well as soluble foreign matter, and in wetting these threads, this matter becomes to some extent 5 dissolved by the water or other liquid. As it passes over the grooved part 15 of the blocks, the excess liquid is expressed therefrom and descends through the bores 16 into the collecting trough 10 from whence it is 10 conducted to any suitable receptacle. This extracted excess liquid will contain more or less of suspended solids and were it returned to the trough, would, after a time, render the liquid more or less thick or mu- 15 cilaginous, which is detrimental. By placing the part or parts 13 outside of or away from the wetting trough and by conducting the excess expressed liquid away from this wetting trough, such action is prevented. It 20 is preferable to maintain a substantially normal liquid level within the wetting trough and any suitable means may be used. In the drawings I show an overflow pipe 19, and a drip feed pipe 20, these parts being 25 merely illustrative of one of many possible means of maintaining a normal liquid level.

The specific structure herein described is productive of numerous advantages as pointed out, but it will be obvious that this 30 structure may be varied within the spirit of the invention and the scope of the appended 35 claims.

What I claim, therefore, and desire to secure by Letters Patent is:

35 1. In a device of the character described, in combination, spool supporting means, a wetting trough, thread feed rolls positioned between said trough and said supporting means, a thread guide supported within said 40 trough under which thread is designed to pass, thread guiding means positioned outside said trough to which thread passes from said trough guide, thread twisting means adjacent said guiding means to which the 45 thread passes from said guiding means, an excess liquid receptacle separate from said wetting trough with means for conducting excess liquid from said guiding means to said receptacle.

50 2. In a device of the character described, in combination, spool supporting means, a trough for liquid, thread feed rolls positioned between said trough and said supporting means, a thread guide supported 55 within said trough under which thread is

designed to pass, supporting means positioned outside of and above said trough, an excess liquid receptacle separate from said wetting trough and mounted upon said supporting means, thread guiding means carried by said receptacle and positioned outside of and above said trough and to which the thread passes from said trough guide, thread twisting means adjacent said guiding means to which the thread passes from 60 said guiding means, and means for conducting excess liquid from said guiding means to said receptacle. 65

3. In a device of the character described, in combination, spool supporting means, a 70 wetting trough, thread feed rolls positioned between said trough and said supporting means, a thread guide supported within said trough under which thread is designed to pass, an excess liquid receptacle positioned 75 above and outside of said wetting trough and a guiding member carried at the top of said receptacle having at least one guiding groove therein through which thread passes from said trough guide, said member also 80 having an excess liquid conducting bore therein communicating with said groove and with said receptacle, and thread twisting means adjacent said guiding member to which thread passes from said guiding 85 groove.

4. In a device of the character described, in combination, spool supporting means, a wetting trough, thread feed rolls positioned 90 between said trough and said supporting means, means supported within said trough under which thread is designed to pass, a metal trough having an open top constructed and supported to extend longitudinally of said wetting trough and above 95 and outside of the same, a block removably held between the walls of said metal trough and above and outside of said wetting trough, said block having at least one thread guiding groove therein to which thread 100 passes from said wetting trough and having a bore therethrough communicating with said groove and with the interior of said metal trough, and thread twisting means to which thread passes from said groove.

WILLIAM WALLACE CALDWELL.
